UNITED STATES PATENT OFFICE.

ARCHER L. KNAPP, OF DETROIT, MICHIGAN, ASSIGNOR TO PACKARD MOTOR CAR COMPANY, OF DETROIT, MICHIGAN, A CORPORATION OF MICHIGAN.

DESIGN FOR AN AUTOMOBILE RADIATOR.

Application filed March 12, 1928. Serial No. 25,809. Term of patent 14 years.

To all whom it may concern:

Be it known that I, ARCHER L. KNAPP, a citizen of the United States, residing at Detroit, county of Wayne, State of Michigan, have invented a new, original, and ornamental Design for Automobile Radiator, of which the following is a specification, reference being had to the accompanying drawing, forming part thereof:

The figure is a front elevation of a radiator for an automobile, showing my new design.

I claim:

The ornamental design for an automobile radiator, as shown.

In testimony whereof I affix my signature.

ARCHER L. KNAPP.
